INVENTOR

GORDON G. BREDIN

BY *Al G. Bredin*
Aug.

UNITED STATES PATENT OFFICE.

GORDON C. BREDIN, OF GALT, ONTARIO, CANADA.

GASOLENE-VALVE.

1,398,999.

Specification of Letters Patent.

Patented Dec. 6, 1921.

Application filed December 13, 1920. Serial No. 430,570.

To all whom it may concern:

Be it known that I, GORDON C. BREDIN, a subject of the King of Great Britain, residing at Galt, in the county of Waterloo and

5 Province of Ontario, Canada, have invented certain new and useful Improvements in Gasolene-Valves, of which the following is a specification.

My invention relates to improvements in 10 valves and more particularly to improvements in valve controlled devices for retaining a reserve fuel supply in the regular tank of a motor vehicle, and consists essentially of a hollow tube extending from the 15 top of the tank to within a close distance of the bottom and having a port a short distance from the lower end, together with means for closing the port.

The primary object of the present invention is to provide a device to serve as a warning when the fuel supply has become low, by temporarily checking the fuel feed.

A further object is to provide an article of the class specified which may be set to 25 retain a predetermined amount of fuel in the supply tank to be used in an emergency such as unexpectedly running low on the supply in order to overcome the liability of exhausting the fuel supply while distant from 30 a source of supply.

A still further object is to provide such a device which will be simple, durable, efficient and comparatively inexpensive to manufacture.

35 These, together with other objects, may be attained by the construction, combination and arrangement of the parts as will be hereinafter more fully described, illustrated in the accompanying drawing, and pointed 40 out in the claim hereunto appended.

Reference being had to the drawing:

Figure 1 is an elevation of the invention;

Fig. 2 is a cross-sectional elevation taken on the line II—II in Fig. 1;

45 Fig. 3 is a top view of the device;

Fig. 4 is a cross-sectional top view taken on the line IV—IV in Fig. 2;

Fig. 5 is a cross-sectional top view taken on the line V—V in Fig. 1;

Fig. 6 is a cross-sectional top view taken 50 on the line VI—VI in Fig. 2; and,

Fig. 7 is a similar view to Fig. 6 showing the valve open.

Similar reference characters refer to similar parts throughout the several views.

55

In the drawing A indicates the top of the fuel tank which is provided with a threaded bushing 2 into which is threaded the head B by means of the hexagon portion 3 thereon.

A perpendicularly disposed tube C is attached to the lower end part of the said head and extends to within a close distance of the bottom of the tank A. The gasolene is sucked or pumped through the tube C by such means as are well known such as the 60 vacuum system, through the feed pipe or "gasolene line" 4 which is connected to a bushing 5 around a neck portion 6 of said head, where the said feed pipe communicates with the core 7 of the head, with which the 65 tube C communicates.

A turn plate D has a neck D' journaled in the upper part of the core 7 in the head B and has a concentric recess into which fits the stem E. The stem is rotatable in a 70 portion of the core 7 of the corresponding diameter and is secured against relative rotation with the turn plate D by the taper pin 8. A ring 9 having corresponding diameter to the upper part of the core 7 and 75 fitting tightly around the stem E, tensionally retains packing 10 in tight relation to the said stem by means of the spiral spring 11 to prevent gasolene leaking past.

A split ring F is swivelly attached to the 80 lower end part of the stem E by means of the pin 12. The ring E comprises a section of tubing minutely larger in its interior diameter than the interior diameter of the tube C, and having a section removed of a 85 width corresponding to the diameter of a port 13 in the tube C, located at a short distance from its lower termination. The split formed by the removal of a section of said ring enables it to be compressed and consequently to be constantly tensionally engaged 90 with the walls of the tube C, and when turned by the stem E to seal the port 13.

The operation of the device is as follows:

When the car is in operation, the port 13, which is located in the tube C at a suitable distance from the bottom of the tank at a point, say, on a plane with the level of a gallon of fuel, is normally open and not closed by the ring F, which position is governed by the position of the turn plate D.

At such turn the word "tank" or other suitable indication is registered with the arrow on the hexagon 3. This position is shown in Figs. 1, 3 and 7.

The fuel is drawn through the end of the tube and through the port 13, but when the fuel level has become lower than the port, air is admitted, and being lighter than the fuel, is sucked through consequently stopping the motor as a warning to replenish the fuel supply. The operator must accordingly give a half turn to the turn plate D which closes the port 13 and permits the remaining amount of fuel to be drawn through the end of the tube C. At this time the arrow adjacent the word, "reserve" for example, is registered with the arrow on the hexagon 3. This position of the valve is shown in Fig. 6.

A pin 14 is provided in the stem E which engages the stop 15 to properly limit the rotary motion thereof.

Having now fully described my invention, what I claim and desire to secure by Letters Patent is:—

In a device of the class described, the combination with a fuel tank, of a tube extending into the depth of the tank and communicating above the tank with a fuel feed pipe, said tube having an opening at its lower end for reception of fuel and having a port at a distance above the opening, a resilient radially expandible split ring formed of a portion of tubing having a longitudinal section removed, rotatable within said tube, adapted to seal said port therein and to open it by rotation of the ring to a point where the split therein registers with said port, and means for rotating said ring from without the tank.

In testimony whereof I have affixed my signature.

GORDON C. BREDIN.
